1,306,439.

Specification of Letters Patent. Patented June 10, 1919.

No Drawing.

Application filed March 30, 1918. Serial No. 225,727.

To all whom it may concern:

Be it known that I, HARLEY W. RHODEHAMEL, a citizen of the United States, residing at Indianapolis, Marion county, and 5 State of Indiana, have invented and discovered certain new and useful Improvements in Compounds of Halogen Acids with 2-Phenyl Quinolin 4-Carboxylic Acid, of which the following is a specification.

10 My invention relates to the previously unknown combinations of halogen acids with 2-phenyl quinolin 4-carboxylic acid.

The compounds may be prepared by treating 2-phenyl quinolin 4-carboxylic acid with 15 an excess of the halogen acid, and then removing the excess acid by drying.

20 2-phenyl quinolin 4-carboxylic acid hydriodid forms orange-yellow crystals which melt at 243° C. This compound is an especially valuable medicinal product, combining as it does the therapeutic properties of 2-phenyl quinolin 4-carboxylic acid and hydriodic acid, both of which are used in the treatment of rheumatism and gout. The 25 hydrobromid forms brownish-yellow crystals which melt at 255° C. The hydrochlorid and hydrofluorid form lemon yellow crystals. The hydrochlorid melts at 223° C.

Having thus described my invention, what I claim is:

1. A compound of 2-phenyl quinolin 4-carboxylic acid and a halogen acid.
2. The hydriodid of 2-phenyl quinolin 4-carboxylic acid.
3. The process of treating 2-phenyl quinolin 4-carboxylic acid with an excess of a halogen acid and then removing the excess acid by drying.
4. The process of treating 2-phenyl quinolin 4-carboxylic acid with an excess of hydriodic acid and then removing the excess acid by drying.

30 In witness whereof, I have hereunto set my hand and seal at Indianapolis, Indiana, this 22nd day of March, A. D. nineteen hundred and eighteen.
